Peter A. Gladwin

UNITED STATES PATENT OFFICE.

PORTER A. GLADWIN, OF PAWTUCKET, MASSACHUSETTS.

SASH-FASTENER.

Specification of Letters Patent No. 22,421, dated December 28, 1858.

To all whom it may concern:

Be it known that I, PORTER A. GLADWIN, of Pawtucket, county of Bristol, and State of Massachusetts, have invented certain new and useful Improvements in Sash-Fasteners; and I do hereby declare that the same is described and represented in the following specification and drawings; and to enable others skilled in the art to make and use the same, I will proceed to describe the construction and operation, referring to the drawings, in which the same letters indicate like parts in each of the figures.

The nature of this improvement consists in constructing a spring catch, or fastener, secured to the meeting rail of window sashes, so that by the pressure of the finger against the thumb piece of the spring catch, at the same time the sash is lifted, will free the sash and when the sash is lowered down will be fastened by the action of the spring catch.

In the accompanying drawings Figure 1, is a face view. Fig. 2, is a sectional view.

A, represents the jamb of the window frame.

B, is the parting strip.

C, represents the meeting rail of the lower casement.

C', represents the meeting rail of the upper casement.

D, is the catch plate.

E, is the spring.

F, is the catches in the spring.

G, is the thumb piece for operating the catch. The thumb piece G is cut into the 35 meeting rail C, about the depth of the lip of the sash, or nearly in a line with the front edge of the parting strip and secured thereto with screws. The catch plate D, is secured on top of and flush with the lip edge of the 40 meeting rail C.

It will be seen that by pulling the thumb piece G, forward, the lower casement may be raised, or the upper casement may be lowered and when brought back to their place 45 will lock or fasten, without further attention.

It is very common, in the use of the ordinary fastenings upon the meeting rail, that windows remain unfastened, which by the 50 use of this improvement is obviated.

The cheapness of the article, its durability, and self-fastening features, constitute the principal advantages it derives over others now in use.

What I claim therefore and desire to secure by Letters Patent is—

The employment of the perforated plate D, with the notched spring F, for fastening window sash, in the manner substantially as 60 described.

PORTER A. GLADWIN. [L.S.]
